CASING FOR A SPACE HEATER OR SIMILAR ARTICLE

Paul A. Jones, Chicago, Ill., assignor to Inland
Steel Container Company, Chicago, Ill., a cor-
poration of Illinois

Application November 5, 1948, Serial No. 149,478

Term of patent 7 years

(Cl. D81—10)

To all whom it may concern:

Be it known that I, Paul A. Jones, a citizen of the United States and resident of Chicago, in the county of Cook and State of Illinois, have invented a new, original, and ornamental Design for a Casing for a Space Heater or Similar Article, of which the following is a specification, reference being had to the accompanying drawing, forming a part thereof.

In the drawing:

Figure 1 is a perspective view of a casing for a space heater or similar article, showing my new design;

Figure 2 is a rear view of the same; and

Figure 3 is a sectional detail taken on the line 3—3 of Figure 1.

I claim:
The ornamental design for a casing for a space heater or similar article, substantially as shown.
PAUL A. JONES.
